UNITED STATES PATENT OFFICE.

GEORGE S. CHILES, OF ST. LOUIS, MISSOURI, ASSIGNOR TO DALMAN, CHILES COMPANY,
A CORPORATION OF DELAWARE.

RAILWAY-CAR TRUCK.

Original application filed May 15, 1922, Serial No. 561,132, now Patent No. 1,493,961, dated May 13, 1924.
Divided and this application filed April 23, 1924. Serial No. 708,360.

This application is a division of my prior copending application, Serial No. 561,132, filed May 15, 1922, (upon which application Patent No. 1,493,961 was granted May 13, 5 1924) and is designed for use in connection with the type of railway car trucks described in said copending application and in my United States Patent No. 1,457,845 granted June 5, 1923. The invention claimed here- 10 in relates more particularly to the bolster construction and the construction immediately related thereto.

Figure 1 is a longitudinal sectional view of the end of a built-up bolster constructed 15 to co-operate with and form part of my improved truck construction.

Figures 2 and 3 are sectional views on lines 2-2 and 3-3 of Figure 1.

Figures 4 and 5 are side elevations of the 20 end and central part, respectively, of a bolster of the type known as the Simplex, but embodying new features adapting it to my invention.

Figure 6 is a view from beneath of the 25 structure shown in Figure 4.

Figure 7 is an end view of the bolster shown in Figures 4, 5 and 6.

Figures 8, 9 and 10 are respectively a 30 plan, side elevation and end view of the end part of a pressed steel bolster similar in general construction, but embodying an end casting of different form.

The bolster shown in Figures 1, 2 and 3 while conforming generally to the type of bolster heretofore in common use and known as the Simplex bolster differs therefrom in the substitution of a channel 105 for the plate used in this part of the Simplex construction, and also differs in the form of the 40 end casting or spring seat member, which latter part in my improved construction is designed to co-operate with an assemblage of springs consisting of a central group supported at a lower level than the outer or end 45 springs as set forth in my copending application and patent above referred to. The elevation of the outer or end springs is clearly indicated in Figure 2 and other views and one mode of disposing the springs 50 horizontally is indicated in dotted lines in Figure 6, the four central springs there shown being supported at a lower level than the outer or end springs. I have substituted the channel 105 for the plate member here-

tofore used in order to increase the trans- 55 verse strength of the bolster. As shown in Figures 1, 2 and 3, the side flanges 107 of the tension member channel of the bolster are folded down near the ends as appears at 60 108. The end casting 106 is secured to the bolster by means of rivets 110 as in the construction heretofore used. The end casting 65 106 is wider than the bolster, being so constructed for the purpose of seating the bolster upon the wide spring assemblage which 70 forms one of the features of my improved truck as fully set forth in my patent and 75 copending application above referred to, but independently of the width of the spring 80 assemblage the end casting is of novel form 85 in order to accommodate springs disposed at different levels, such disposition of the 90 springs having advantage regardless of the total width of the assemblage. The bottom 95 wall of the end casting shown in Figures 1, 2 and 3, has a central part, 1, on a lower level than the end parts, 2, the end sections being connected to the central section by the 100 vertical wall sections, 4. The vertical side 105 walls, 5, are spaced apart just sufficiently to receive between them the downwardly ex- 110 tendsing side flanges, 6, of the channel 109 which forms the compression member of the 115 bolster. In order to accommodate a wide 120 spring assemblage the projections 111 are 125 provided, each of these projections having 130 two vertical walls 7 projecting from the 135 wall 5 and joined at their outer extremities by the wall 8 parallel to the wall 5. The 140 box-like projection so formed is closed at 145 the bottom, as indicated at 9 by an extension 150 of the elevated part 2 of the bottom wall of the casting. The projections 111 are of less 155 extent longitudinally of the bolster than the 160 central part of the casting for the reason 165 that the particular casting illustrated is de- 170 signed for a spring assemblage such as illus- 175 trated in Figure 6 where single end 180 springs 10 obviate the necessity of making 185 the projections 111 of the full width of the 190 end casting. Extending upward from the 195 part 1 of the bottom wall are two vertical 200 webs 3, 3, which with the rear wall 12 sup- 205 port the inclined top plate 11 which under- 210 lies the lower or tension member of the bol- 215 ster and is riveted thereto. The bolster ten- 220 sion member 105 is at its end folded over 225 the end of the bolster compression member 230 105

109, there being a filler plate 13 interposed between these members and rivets passing through both the tension and compression members and filler plate as shown. The structure shown in Figures 4, 5, 6 and 7 is of a form in common use and known as the Simplex bolster. In these views I show the method commonly used heretofore for joining the tension and compression members 10 and end casting in place of my improved means illustrated in Figures 1 to 3. The form of the spring seat on the under side of the casting, the projections 111 and the relations of these parts to each other are 15 similar to the structure shown in Figures 1 to 3. The bottom and side walls of the end casting shown in Figures 4 to 7 are secured by rivets 112 to the tension member 107 (Fig. 4), and to the downwardly directed side 20 flanges 150 of the compression member, (which latter is designated generally by the numeral 151) as shown in Figures 4, 6 and 7.

In the construction shown in Figures 8, 9 and 10 the bolster shown comprises a lower 25 longitudinal member of U-shape cross section, as shown most clearly in Fig. 10, and with out-turned flanges 153 at the upper edges of the side walls. This lower longitudinal member is of greater depth at the 30 center as indicated by the downwardly inclining bottom wall 155 (Fig. 9) thereby better resisting the tension stresses, and the upper plate 154 which is riveted to the out-turned flanges 153, forms a compression member. 35 The end casting shown in Figures 11 to 13 takes the form of a box which slips over the end of the bolster, and the projecting sides 121 of the end casting are of less vertical depth than the bolster and the central part 40 of the casting, thereby providing higher seats beneath the bolster for the end springs than for the central group of springs. As clearly appears in Figure 11, the side walls of the bolster 122 are brought closer together at 124 at the end of the bolster in 45

order to afford clearance for the end springs 123.

I claim:

1. In a railway car truck, a bolster comprising a longitudinal section having a 50 spring seat at each end, each of said spring seats being of greater width than the intermediate longitudinal part of the bolster and projecting transversely thereof, the central part of each of said spring seats being at a 55 lower level than the transversely projecting end parts.

2. In a railway truck, a bolster comprising separate compression, tension and spring seat members, each of said spring seat members being of greater width than said tension and compression members and forming a spring seat the end parts of which project transversely of the bolster beyond said compression and tension members, the central part of said spring seat being at a lower level than the end parts, springs co-acting with said spring seat, and means for attaching said compression, tension and spring seat members together. 70

3. In a railway car truck, a bolster comprising separate compression, tension and spring seat members, each of said spring seat members being provided with means for engaging springs supported with their upper 75 ends at different levels, and means for attaching said compression, tension and spring seat members together.

4. In a railway car truck, a bolster comprising separate upper and lower longitudinal members and spring seat members at the opposite ends thereof, each of said spring seat members being provided with means for engaging springs supported with their upper ends at different levels, and means for attaching said upper, lower and spring seat members together. 80

Signed at Lima, Ohio, this 19th day of April, 1924.

GEORGE S. CHILES.
